UNITED STATES PATENT OFFICE.

FRANCIS T. PETERS, OF DECATUR, ILLINOIS.

REPLACEABLE LADDER RUNG.

Application filed January 30, 1922. Serial No. 532,544.

To all whom it may concern:

Be it known that I, FRANCIS T. PETERS, a citizen of the United States, and a resident of Decatur, in the county of Macon and

5 State of Illinois, have invented a new and useful Improvement in Replaceable Ladder Rungs, of which the following is a full, clear, and exact description.

10 My invention relates to improvements in replaceable ladder rungs, and it consists in the combinations, constructions and arrangements herein described and claimed:

15 An object of my invention is to provide a device of the character described, which may be secured directly upon the ladder rail without any special preparation of the rails.

20 A further object of my invention is to provide a device of the character described which is extremely simple in construction and which may be manufactured from a single piece of stock.

25 Other objects and advantages will appear in the following specification, and the novel features of the invention will be particularly pointed out in the appended claim.

My invention is illustrated in the accompanying drawings, forming part of this application, in which—

30 Fig. 1 is a perspective view of an embodiment of my invention,

Fig. 2 is an enlarged perspective view of one end of the ladder rung, and

Fig. 3 is an enlarged view of a modified form of the ladder rung.

35 In carrying out my invention, I make use of ordinary ladder rails 1 and 2, which are not previously prepared in any way, except that their inner faces may be smoothed by a plane. The rails 1 and 2 are placed in 40 substantial parallel relation to one another if the ladder is to be of the straight type.

The rungs are composed of single pieces of angle iron 3 having sides 4 and 5 at right angles to one another and of equal width.

45 In preparing the means for fastening the rung or angle iron 3 to the rails 1 and 2, a slit is made at the intersecting points of the sides 4 and 5 adjacent each end of the angle iron 3. This slit is substantially the 50 same depth as the width of one of the sides 4 and 5.

The side 5 is thereupon bent laterally at each of its ends on the line 6, which line is transverse to the rung 3 and disposed at the 55 bottom of the slit previously described. The

laterally bent portions 7, thus formed, of the side 5 are disposed so that they are each in exact perpendicular planes to the sides 4 and 5.

Laterally bent portions of the side 4 are 60 bent along the lines 8 transverse to the side 4 and disposed at the base of the slit previously described. The laterally bent portions 9 of the side 4, thus formed, are also in exact perpendicular planes to the sides 4 65 and 5 of the angle iron 3. The laterally bent portions 7 and 9 are therefore both in the same plane and their surfaces contiguous.

70 Centrally located openings 10 and 11 are provided through the portions 7 and 9, respectively, and provide means for receiving wood screws 12 for securing the rung 3 to the rails 1 and 2. The inner surfaces of the portions 7 and 9 adjacent the openings 10 and 11 are countersunk, as shown at 13, to 75 accommodate the head of the wood screws 12.

75 From the foregoing description of the various parts of the device, the operation thereof may be readily understood. The rung 3 may be used as a replacement rung, that is, 80 to take the place of the ordinary type of spindle rung which has come loose from its engagement with the rails 1 and 2 of the ladder by breakage or the like and for this purpose it is merely necessary to place the rung 3 so that its laterally bent portions 7 and 9 are in contact with the inner surfaces 85 14 of the rails 1 and 2 and wood screws 12 inserted through the openings 10 and 11 and turned tightly into the rails. 90

The rungs 3 may also be used to great advantage in the construction of new ladders, since the assembly thereof is certainly cheap and quick, it being merely necessary to apply the screws 12 through the openings 10 and 95 11 to secure the rungs 3 in their proper respective positions relative the rails 1 and 2.

100 In Fig. 3, I have shown a modified form of the rung 3 in which I weld the adjacent edges of the laterally bent portions 7 and 9 to form one continuous surface 15 of the portions 7 and 9. This also adds greatly to the strength of the fastening means and also to the angle iron itself, since the laterally bent portion 9 becomes an integral web for 105 the intersecting sides 4 and 5 of the angle iron 3.

I claim:

110 A device of the character described comprising an angle iron having laterally bent

portions of its two respective sides at each other side being bent to provide a web beyond thereof, the laterally bent portions of the two respective ends being disposed in a single plane transverse to the body portion of the angle iron, each of said bent portions being provided with an opening therethrough to receive a wood screw or 10
5 of the angle iron, the laterally bent portions the like. at one side being bent away from said angle iron and the laterally bent portions of the

FRANCIS T. PETERS.
